UNITED STATES PATENT OFFICE

JAMES A. DAVEY, OF SOUND BEACH, CONNECTICUT, AND PAUL H. DAVEY AND CHARLES L. GAUGLER, OF KENT, OHIO; SAID GAUGLER ASSIGNOR TO THE DAVEY TREE EXPERT CO., OF KENT, OHIO, A CORPORATION OF OHIO

PORTABLE COMPRESSOR AND MEANS FOR MOUNTING THE SAME ON TRACTORS

Application filed May 27, 1927. Serial No. 194,704.

Our said invention relates to a portable compressor and means for mounting the same on a tractor, which may be of the Fordson type. It is a matter of great convenience 5 and economy to be able to mount a compressor on a power generator which can travel from place to place under its own power and which is itself inexpensive and of light weight. It is an object of our invention to provide a 10 compressor which is itself light and of simple construction, but which is of large capacity, with means for attaching it to a tractor.

This application is, in part, a continuation 15 of our application Serial No. 703,098, filed March 31, 1924.

Another object is to provide improved means for readily connecting the compressor driving means to a driven shaft of the tractor.

Referring to the drawings, which are made 20 a part of this application, and in which similar parts are indicated by similar reference characters:

Fig. 1, is a side elevation of a Fordson tractor with the compressor of our invention 25 applied thereto,

Fig. 2, a vertical longitudinal section of a part of the compressor,

Fig. 3, a vertical section of the compressor,

Fig. 4, a cross-section illustrating a preferred means of connecting the driving means 30 of the compressor and the tractor.

Fig. 5, an elevation of a part of the compressor, viewed from the right in Fig. 4, and

Figs. 6 to 9, details of parts shown in 35 Figs. 4 and 5.

In the drawings, reference character 10 indicates generally a tractor of the type referred to, said tractor having an opening in the side of the crank case for attachment of 40 a belt pulley or the like in well-known manner. The driving shaft of the compressor, or an operative connection from the same, is entered through this opening for driving engagement with suitable means on a shaft of 45 the tractor, e. g., the main shaft extending lengthwise thereof. A clutch (not shown) serves to disconnect the compressor when the tractor is to be moved.

In the embodiment here shown the compressor 50 has a crankshaft 11 with a crank pin

12 connected to pitman rods 13 which actuate pistons 14 in the cylinders 15 at opposite ends of the compressor crank casing 16.

A flywheel 17 at each side of the crank pin serves to steady the operation of the pistons and helps to overcome the violent reactions due to the sudden changes of pressure in the cylinders. The cylinders are provided with fins 18 for cooling them.

Each cylinder is connected directly to a 60 reservoir 19, this reservoir being preferably made of aluminum or other metal having a high heat conductivity and provided with cooling fins 20. As best shown in Figure 2, each reservoir is directly connected to its corresponding cylinder and the cooling fins 20 together with cooling fins 18 on the cylinder proper are effective for maintaining the entire apparatus at the desired low temperature.

Each reservoir 19 is provided with an opening 70 in line with the cylinder 15 and adapted to receive a basket-like frame member 21 for supporting the inlet and outlet valves of the cylinder. The frame member 21 comprises a central tube 22 having inwardly projecting lugs 23 for supporting a cross bar 24. A bolt 25 passes through the cross bar and is threaded into a valve seat 26 having inlet ports 27 therein. A valve 28 is normally held against the seat 26 by springs 29 which are carried by a spider 30. On the inlet stroke of the piston 14 air passes through the central tube 22 past the cross bar 24 and through the openings 27 into the cylinder. On the return stroke the air is compressed and leaves the 80 cylinder through openings 31 in the valve seat 26, past a valve 32 normally held against the seat by springs 33, and into the reservoir 19. When the compressed air is discharged into the reservoir it spreads outwardly and 85 impinges on the walls thereof. This greatly facilitates cooling and aids materially in maintaining the compressor at the desired low temperature, due to the high heat conductivity of the reservoir, and of the valve seat 26, preferably made of aluminum.

The basket frame 21 is held in place by cap screws 34 and when these are removed the entire valve structure, as well as the interior of the cylinder and the reservoir, is immediately 90 100

accessible. The basket and the valve structure are removable as a whole from the compressor and the inlet valve may be replaced by removing a screw 35 which holds the spider 30 in place, while the outlet valve may be replaced by loosening the bolts 25, turning the cross bar 24 until it is free of the lugs 23 and removing the valve plate 26 from the basket frame 21.

10 The reservoirs 19 are connected by a conduit 36 and air may be withdrawn from the compressor through a connection 37 which is preferably provided with a relief valve. The conduit 36 is preferably large, since this allows a very rapid communication of pressures between the reservoirs. As will be apparent from the drawings, the two cylinders alternately discharge compressed air and the conduit 36 serves as an equalizer for the compressor. Ordinarily it will be found that the two reservoirs will be ample for any use to which the compressor may be put and air may be taken from the connection 37 directly to the air driven tool. In some cases it may be desirable to interpose an additional reservoir in the system and this can be readily accomplished. In any event, the provision of a reservoir immediately adjacent the cylinder is of value, particularly in a portable compressor of this type, which it is proposed to operate at high speeds with air cooling.

15 A pair of fans 39 and 40 may be mounted on pivots 41, 42 projecting from the reservoirs 19 and may be driven by a belt 43 passing over 20 a pulley 44 on the shaft 11, these fans serving to further cool the reservoirs.

25 In the construction shown in Figs. 4 to 9 a part of the crank case is indicated at 47 with an opening to receive a sleeve 48 having a flange 49 secured to the crank case by screws 50. The attachment plate or supporting plate 51 for the compressor housing 52 has a cylindrical extension 51' slidably mounted in sleeve 48 and has a bronze bushing 53 providing a bearing for the shaft 54 of the compressor, which shaft carries a bevel gear 55 having teeth engaging those of a gear 56 of the main shaft 57 of the tractor. A ball bearing 58 is interposed between the gear 55 and a shoulder on the supporting plate. A second bronze bushing 59 is located between the shaft 54 and the housing 52, said bushing being separated from bushing 53 by a washer 60 resting against a shoulder on the supporting plate.

30 Adjacent parts of the sleeve 48 and the extension on the supporting plate 51 are reversely threaded and a ratchet 61 has threads engaging the threads of parts 48 and 51 for moving the plate 51, the compressor and the shaft 54 axially of said shaft to bring the gear 55 into or out of engagement with the gear 56. A lever 62 for operating the ratchet is formed at its lower end with a cavity, closed 35 by a plate 63, in which a pawl 64 is movably

supported, said pawl being held in engagement with the ratchet by a spring 65. The pawl at its lower end is beveled, as shown in Fig. 5, so as to slip over the ratchet teeth in one direction.

40 Splines 66 (Fig. 5) engage corresponding grooves 67 and 68 in parts 48 and 51' (Figs. 8 and 7) to prevent rotation of the extension 51' and parts attached thereto. Except as noted the compressor of Fig. 4 may be as in 45 our application Serial No. 15,717 filed March 16, 1925.

45 It will be evident from the foregoing that when the tractor is to be moved the lever is moved in a direction to turn the ratchet so as to back off the compressor, the plate 51, extension 51', shaft 54, and gear 55 away from gear 56. When the compressor is to be used the pawl is turned to cause it to move the ratchet in the opposite sense and the operation 50 is repeated in reverse order to bring the gears into engagement.

55 It will be obvious to those skilled in the art that the device of our invention can be changed in various respects without departing from the spirit of the invention and therefore we do not limit ourselves to the particular mechanisms shown in the drawings and described in the specification but only as indicated in the appended claims. For example, it is within the contemplation of my invention to attach the compressor to a truck or other motor vehicle in the manner indicated.

60 Having thus fully described our said invention, what we claim and desire to secure by Letters Patent is:

65 1. The combination of an engine-driven tractor, a portable compressor carried thereby said compressor being of a capacity requiring substantially the entire power of the engine, and means for moving the compressor bodily toward and away from the tractor to bring it into and out of driving engagement with a shaft of the tractor.

70 2. The combination of a tractor having a driving shaft, a portable compressor carried by the tractor, and means for moving the compressor bodily toward and away from the tractor to bring it into and out of driving engagement with said driving shaft, said means comprising reversely arranged threads on adjacent cylindrical parts of the tractor and the compressor, an annular member having internal threads engaging the first-named threads, and means to rotate said annular member.

75 3. The combination of a tractor having a driving shaft, a portable compressor carried by the tractor, said compressor having a shaft, and means for moving the compressor bodily toward and away from the tractor to bring its shaft into and out of driving engagement with said driving shaft, said means comprising reversely arranged threads on adjacent cylindrical parts of the tractor and the com- 80

pressor, an annular ratchet having internal threads engaging the first-named threads, and means to rotate said ratchet.

4. A device as in claim 3, said last-named means including a reversible pawl.

5. The combination of a tractor having a driving shaft, a portable compressor carried by the tractor, a sleeve secured to the crank case of the tractor, an extension on the housing of the compressor splined to said sleeve, and means to move the compressor bodily toward and away from the tractor to bring it into and out of driving engagement with said driving shaft.

15 6. The combination of an engine-driven tractor having a driving shaft, a compressor of a capacity requiring substantially the entire power of the engine for driving it, said compressor having a shaft driven from said engine shaft, a pair of aligned cylinders parallel to the longitudinal axis of the tractor and arranged at opposite sides of the compressor shaft, and pistons in said cylinders driven by said compressor shaft.

20 7. The combination of an engine-driven tractor having a driving shaft, a portable compressor of a size requiring substantially the entire power of the engine for driving it mounted at one side of the tractor in a position normally provided on standard tractors of this type for a power take-off, said compressor having a shaft extending horizontally outward from the tractor, and means for connecting said shaft of the compressor to said driving shaft.

25 8. The combination of an engine-driven tractor having a driving shaft, a portable compressor of a size requiring substantially the entire power of the engine for driving it mounted at one side of the tractor in a position normally provided on standard tractors of this type for a power take-off, said compressor having a shaft extending horizontally outward from the tractor, means for connecting said shaft of the compressor to said driving shaft, and manually operable means to connect said shafts.

30 9. The combination of an engine-driven tractor having a driving shaft, a portable compressor of a size requiring substantially the entire power of the engine for driving it mounted at one side of the tractor in a position normally provided on standard tractors of this type for a power take-off, said compressor having a shaft extending horizontally outward from the tractor, means for connecting said shaft of the compressor to said driving shaft, gears on said shafts, and manual means to engage said gears directly with each other.

35 In testimony whereof we affix our signatures.
